PORTABLE COACH BODY FOR CAMPING OR THE LIKE

Roy H. Fogelsonger, 5838 San Fernando Road,
Glendale, Calif.

Filed Sept. 17, 1959, Ser. No. 57,587

Term of patent 14 years

(Cl. D14—3)

Fig. 1 is a rear perspective view of a portable coach body for camping or the like, showing my new design, the truck shown in the dotted lines being included for illustrative purposes only, and

Fig. 2 is a front perspective view of a portable coach body for camping or the like as shown in Fig. 1, the coach body being shown as used for camping.

I claim:

The ornamental design for a portable coach body for camping or the like, substantially as shown.
